UNITED STATES PATENT OFFICE.

CONRAD ROSINE, OF CHICAGO, ILLINOIS.

ADJUSTABLE FAN.

Application filed May 22, 1926. Serial No. 110,890.

This invention relates to adjustable fans and its principal object is to provide an air circulating fan having adjustably mounted fan blades and novel adjustment means, controllable from a remote place, for adjusting the angular position of the fan blades while the fan is in motion. In its present form the fan has been designed for use in connection with the motor of an automobile or other motor driven vehicle, and the fan blade adjustment means and fan blades are so constructed and arranged that air may be forced against the motor, or air may be exhausted from underneath the usual hood which covers the motor, or the fan blades may be set to act as a sort of partition between the motor and outside air. Another object of this invention is to provide a simple, substantial and rugged fan blade adjustment mechanism, to prevent rattling and other objectionable noises and to increase the efficiency of fans of this character. With these ends in view this invention consists in the several novel features hereinafter fully set forth and claimed.

The invention is clearly illustrated in the accompanying drawing, in which:

Fig. 1 is a front elevation of an adjustable fan, partly broken away, embodying one form of the present invention; Fig. 2 is a side elevation of the fan seen in Fig. 1 partly broken out to show parts that would otherwise be hidden from view; Fig. 3 is a horizontal section taken on the line 3—3 of Fig. 2 and Fig. 4 is a plan of a slightly modified form of the invention, partly broken away.

Referring to said drawing and first to Figs. 1, 2 and 3, which illustrate the preferred embodiment of the invention, the reference character 5 designates a fragment of a bracket arm or support, such as is usually employed for supporting the fan assembly on the motor block of the engine of an automobile or other motor vehicle. Secured to and supported by the bracket arm 5 is a stationary spindle or arbor 6 upon which the fan pulley 7 and fan 8 are rotatively mounted. The fan pulley has a hub portion which is shown in the form of a sleeve 9 upon which the fan pulley is secured, as for instance by a driving fit and by a set screw 10 if desired, and end wise movement of said pulley hub or sleeve and the parts carried thereby is prevented by shoulders 11, 12 at the ends of the spindle 6. The

bearing construction illustrated is merely schematic, as any well known type of bearing may be employed for the pulley and fan.

Secured to the outer end of the pulley sleeve or hub 9 are spindles 13, which extend in radial directions from the sleeve and are spaced equidistantly. Swiveled or rotatively mounted on each spindle 13 is a fan blade 14 which is preferably flat and formed of sheet metal and may be of substantially rectangular form. For the sake of simplicity and convenience in manufacture, each fan blade is formed with alternate and intermediate half round depressed portions 15 along its axis of rotation, the alternate depressed portions extending on one side of the blade and the intermediate ones on the other, and forming a socket like arrangement for the reception of the spindle 13. On each spindle 13 is secured a collar 16 as by pinning it thereon, which collar stands in an opening formed between two of the depressed parts 15 and prevents end wise movement of the fan blade. On account of the swivel connection between the fan blades and spindles, the fan blades may be swung or partially rotated on the spindles to bring the fan blades into one and the same plane, or to bring them into any angle, within given limits, with respect to said plane.

Adjustment means are provided for adjusting the angularity of the fan blades from any remote place, as for instance from the dash board or instrument board of an automobile, or from any convenient place adjacent the driver's seat in the vehicle, and the means illustrated will now be described.

Slidably mounted in the body or end wall 17 of the fan pulley 7, and along lines parallel with the axis of the spindle 6 are plungers or stems 18, one for each fan blade, each plunger or stem being connected to an associated fan blade by a connecting link 19. Conveniently the outer ends of the plungers or stems 18 are forked and the ends of the links 19 are pivotally held between the forks by pins 20. The outer ends of the links are formed with apertures in which are held headed pins or studs 21 that are riveted or otherwise fastened to the fan blades. The construction and arrangement of the connecting means between the fan blades and plungers or stems 18 is merely illustrative, and may be varied by the substitution of equivalent connections therefor.

It will be understood that by moving the plungers or stems 18 back and forth in unison in their bearings in the fan pulley, the fan blades are thereby partly rotated or turned in unison upon their spindles, from the extreme oblique position seen in Fig. 2 to an extreme oblique position oppositely inclined with respect thereto.

The fan pulley is made hollow as shown 10 and in the hollow thereof is a disc like member 22 to which the plungers or stems 18 are rigidly secured, and as a preference, by being screwed therein. Said disc like member 22 forms part of a sliding collar mechanism 23 which is connected to a forked operating rod 24 that runs to some convenient place adjacent the driver's seat, where it is provided with any suitable means for holding it in adjusted positions, but as this 20 feature forms no part of the present invention it will not be described in detail. The sliding collar mechanism 23 illustrated, comprises a collar 25 rotatively mounted on the disc like member 22 by ball bearings so as to minimize the friction, the balls being held in ball races formed in the sides of the collar 25 and in the adjacent sides of the disc like member 22 and a ball ring 26, which is connected to the disc like member 22 by a 25 sleeve 27, which as shown is formed as a part of the disc like member 22. The ball ring 26 is shown as threadedly secured on the sleeve 27 for the purpose of adjustment and a lock nut 28 is threadedly secured on the sleeve beyond the ball ring 26 to lock the same in adjusted position. Arms 29 secured to the collar 25 and to the operating rod 24 connect the sliding collar mechanism 30 with said operating rod.

It will be observed that although the operating rod 24 holds the collar 25 stationary, the fan pulley, its hub, the fan and connections with the disc like member 22 and other members of the ball bearing device for the collar 25, are free to rotate, and in practice a fan belt (not shown) is trained over the fan pulley and is driven by some motor driven fan pulley.

To change the angular position of the fan 50 blades from the position shown in the drawing, the operating rod 24 is drawn back, thereby drawing back the sliding collar mechanism 23, the plungers 18, links 19, and the sides of the fan blades to which the links are attached. In this manner the fan blades may be set at any desired angle, within given limits, with respect to the plane of rotation of the fan. The adjustment members may be drawn back far enough to 55 bring the fan blades into alignment with each other, whereby they will act merely to cut through the air without moving it. The adjustment means may be drawn farther back thereby bringing the fan blades into oblique positions disposed in directions op-

posite those in which they are shown in the drawing.

In modified form illustrated in the Fig. 4 the parts are substantially the same as the corresponding parts shown in Figs. 1, 2 and 70 3. In place of the arms 29 between the collar 25 and operating lever 24, the collar 25a itself is formed with radially extending pins or studs 29a for connection with the operating rod. In this case the forked end of 75 the operating rod is connected directly to the collar 25a.

Among the advantages of this invention are its simplicity, its ruggedness, strength, durability and great efficiency. When used 80 in connection with a motor of an automobile, the driver may regulate the amount of cold air supplied to the motor. For instance on cold days he may adjust the fan blades so as to stand in a plane parallel of the plane of 85 rotation of the fan or he may adjust the fan blades so as to direct the current of air in an outward direction from the hood. If he finds that the motor is heating more than necessary he may adjust the fan blades so as 90 to deflect the fan blades into a position where they act to move air to and under the hood. Furthermore the driver may set the fan blades so as to increase or decrease the amount of air moved by the fan in either 95 direction.

More or less variation of the exact details of construction is possible without departing from the spirit of this invention; I desire, therefore, not to limit myself to the 100 exact form of the construction shown and described, but intend, in the following claims, to point out all of the invention disclosed herein.

I claim as new, and desire to secure by 105 Letters Patent:

1. In an adjustable fan, the combination of a rotatively mounted hollow fan pulley having a hub extension of smaller diameter than the pulley, fan blades swiveled on one 110 end of said hub extension, sliding collar mechanism slidably mounted in the hollow of said fan pulley, an operating rod connected to said sliding collar mechanism, fan blade adjusting plungers, one for each fan 115 blade, slidably mounted in the fan pulley body and located externally of the hub extension thereof, said plungers being rigidly secured to a member of said sliding collar mechanism, and connecting links, one for each fan blade, and directly connected thereto, and pivotally connecting a plunger with an associated fan blade externally of said hub extension.

2. In an adjustable fan, the combination 125 of a rotatively mounted hollow fan pulley having a sleeve like hub portion of smaller diameter than the pulley and extending beyond one end of the fan pulley, radially extending spindles rigidly secured to the outer 130

- end of the extended part of said hub portion of the pulley, fan blades, one swiveled on each spindle, sliding collar mechanism slidably mounted to move into the hollow of 5 the fan pulley, an operating rod connected to said sliding collar mechanism, fan adjusting plungers, one for each fan, slidably mounted in the fan pulley body, and located externally of said hub portion, said plungers 10 being rigidly secured to a member of the sliding collar mechanism, and connecting links, one for each fan blade, and directly connected thereto, and pivotally connecting a plunger with its associated fan blade externally of 15 said hub portion.
3. In an adjustable fan, the combination of a rotatively mounted hollow fan pulley having a hub extension of smaller diameter than the pulley, fan blades swiveled on one 20 end of said hub extension, sliding collar mechanism having a plunger actuating member and a collar rotatively mounted thereon, said sliding collar mechanism being slidably mounted in the hollow of said fan 25 pulley, an operating rod connected to the collar of said sliding collar mechanism, fan adjusting plungers, one for each fan blade, slidably mounted in the fan pulley body and located externally of said hub extension, said plungers being rigidly secured to said 30 plunger actuating member of the sliding collar mechanism, and connecting links, one for each fan blade and directly connected thereto, and pivotally connecting a plunger with its associated fan blade externally of 35 said hub extension.
4. In an adjustable fan, the combination of a rotatively mounted hollow fan pulley having a sleeve like hub portion of smaller 40 diameter than the pulley, radially extending spindles rigidly secured to one end of said hub portion, fan blades swiveled on said spindles, slidable collar mechanism slidably mounted on said sleeve like hub portion within the hollow of the fan pulley, an operating rod connected to said sliding collar mechanism, fan adjusting plungers, located externally of said hub portion, there being one for each fan blade, rigidly secured to a member of said sliding collar mechanism, 45 and connecting links, one for each fan blade, and directly connected thereto, and pivotally connecting a plunger with its associated fan blade externally of said hub portion.

CONRAD ROSINE.
